tion of New Jersey

Original application June 20, 1930, Serial No.
462,441. Divided and this application Decem-
ber 22, 1931. Serial No. 582,545

2 Claims. (Cl. 222—7)

This application is a division of application Serial No. 462,441, filed June 20, 1930.

This invention relates particularly to the treatment of cement raw material in rotary kilns, to which the raw material is fed preferably in the shape of nodules or pellets, which may be formed by adding water to dry pulverulent materials and shaping them by suitable mechanical means, such as a pug mill, or which may be formed by suitable mechanical means from the filter cake of slurry filters, with the possible addition of dry dust. The principal object of the invention has been to secure greater fuel economy than has been possible hitherto in the operation of rotary kilns, in which, as is well understood, the transfer of heat from the combustion gases to the material has not attained the maximum degree which would be desirable and the combustion gases have therefore left the kiln at a relatively high temperature. In seeking to attain the main purpose of the present invention and a more nearly complete transfer of heat from the combustion gases to the material treated, with less loss of heat in the escaping gases, it has been sought to expose to the action of the combustion gases the largest possible surface of the raw material, during the passage of the gases in one direction and the passage of the material in the opposite direction, and to bring about a more intimate contact between such materials and the gases than has been possible heretofore in the operation of rotary kilns. At the same time it has been sought to keep the length of the kiln within reasonable limits. With the more effective transfer of heat from the combustion gases to the material in the calcining zone of the kiln, accomplished as explained in said application Serial No. 462,441, the gases which pass therefrom into the preliminary heating and drying zone or section of the kiln are at a lower temperature than has been usual heretofore and therefore while they are sufficiently hot to accomplish the desired drying and preliminary heating, especially when the drying and heating are carried out as will be explained, they are not at such high temperature as to have a destructive effect upon the structural elements of the drying and heating zone or section of the kiln. The invention will be more fully explained hereinafter with reference to the accompanying drawing in which it is illustrated, and in which:

Figure 1 is a somewhat diagrammatic view, in longitudinal, sectional elevation, of a kiln which is adapted for the practice of the invention.

Figure 2 is a detail view in transverse section, through the drying and heating zone or section of the kiln, on the plane indicated by the broken line 5—5 of Figure 1.

Figures 3 and 4 are detail views illustrating the preferred construction employed in the drying and heating zone or section.

The sections of the kiln adapted to contain the clinkering zone, the calcining zone, and the heating zone, are indicated generally in Figure 1, at A, B and C, respectively, and the material forming and feeding mechanism is indicated conventionally at D.

The clinkering zone or section A of the kiln may be of any usual or suitable construction, being provided, as indicated at a, with a suitable fuel supply and, as indicated at a¹, with a suitable discharge for the hot clinker.

The calcining zone or section of the kiln is made up of a main cylindrical portion or shell b and a series of tubes b¹ and b². In the arrangement shown in Figure 1 the shell b is closed at its upper end by a partition b³ and each tube b¹ is connected at its upper end, as at b⁴, with an extended shell of the kiln above the partition b³, so that the material which has been dried and heated in the zone or section C is delivered therefrom into all of the tubes b¹. Each of the tubes b¹ is connected, as at b⁵, with the corresponding tube b² which in turn is connected at its upper end, as at b⁶, with the main part b below the partition b³, so as to deliver the material received by it from the tube b¹ into the main part b of the kiln. The material which is received from the heating zone C passes, under the influence of gravity, in the operation of the kiln, through the tube b¹ to its lower end and is delivered therefrom, under the influence of gravity, through the connection b⁵, into the lower end of the corresponding tube b² which is provided interiorly with flights b⁷ by which, in the continued rotation of the kiln, the material is caused to move toward the upper end of the tube b² whence it is delivered through the connection b⁴ into the main part b. It will be understood that the combustion gases pass from the upper end of the calcining zone into the tubes b¹ and thence into the tubes b² and thence into the heating zone in countercurrent as to the movement of the material. It will be further observed, not only that there is a great surface of material exposed to the action of the combustion gases in the long path of movement of the material from the time it enters the tubes b¹ until it leaves the calcining zone, but that in the rotation of the kiln, the material in the tubes b¹ and

material from the time it enters the tubes b¹ until it leaves the calcining zone, but that in the rotation of the kiln, the material in the tubes b¹ and

*b*², as well as in the main part *b*, is continually shifted with the result that intimate contact of the combustion gases and the material is accomplished. It will further be observed that while 5 the ratio of exposed internal surface of the sintering zone or section to the cross-sectional area of the zone may be normal, through the construction described, the ratio of the exposed surface of the calcining zone to the cross-section of that zone, 10 which is an important factor in the transfer of heat to the material, through radiation from that portion of the lining which is not covered by the material, is greatly increased as compared with that permitted in a single tube kiln, while 15 at the same time the length of the calcining zone is kept within reasonable limits. In such a structure as that illustrated in the drawing, with the calcining zone 80 feet in length and the main part of the kiln 10 feet in diameter, and the tubes *b*¹ 20 and *b*² corresponding in diameter about as indicated, it is easily possible to create a ratio between the exposed surface of the calcining zone and its cross-section of upwards of 200:1.

The heating zone *C* is so constructed that the 25 gases which enter it from the calcining zone, relatively reduced in temperature but still hot enough to effect the desired purpose of the conditions to be described, are compelled to pass through the material as it is received in the heating zone and 30 while it continues to move therein from the upper or feed end to the lower end of that zone where it passes into the tube *b*¹. To accomplish this the shell *c* is perforated throughout its length and throughout its circumference, as indicated at *c*¹ 35 in Figures 1, 2 and 3. The shell *c* is preferably provided with a lining *c*² of metal boxes or ducts, as shown, which may be grouted in position against the inner wall of the shell, covering the opening *c*¹ in the shell and provided with openings *c*³. There is provided about the shell *c* a housing 40 *c*⁴, which may be provided with a damper-controlled cooled air inlet, as at *c*⁵. The housing is also connected, as indicated at *c*⁶, with an ex- 45 hauster *c*⁷ which draws the combustion gases through the kiln and through the bed of material in the heating zone and may discharge such gases into a suitable stack *c*⁸. In order to prevent the combustion gases from passing directly from the shell *c* within the housing without passing 50 through the bed of material in the shell *c*, there are provided gas guards *c*⁹ and *c*¹⁰ which are secured to the housing and rest at their edges against the shell *c*, in such relation to the material 55 in the shell *c*, as represented in Figure 2, so that practically all of the combustion gases which are received in the heating zone *C* from the calcining

zone *B* are compelled to pass through the bed of material in the shell *c*.

It will be understood that such of the material as enters the shell *c* in the form of dust or is produced in dust form in the shell by the possible breaking of nodules or pellets, will pass through the perforations in the lining and in the shell and will fall to the bottom of the housing *c*⁴ where there may be provided a conveyor *c*¹¹ by which the dust may be conducted to an elevator *d* for return to the nodule forming mechanism illustrated conventionally in Figure 1.

It will be understood that the upper end of the shell *c* is closed, except for the chute *d*¹, by which the material is delivered to the shell from the nodule forming mechanism so that the escape of combustion gases at this point shall be reduced to a minimum. The devices for handling the material preparatory to its introduction into the kiln may be of any suitable character. The apparatus shown comprises a hopper *d*², something in the nature of a pug mill *d*³, water supply *d*⁴, and a dust chute *d*⁵.

Various changes in details of construction and arrangement can be made to suit different conditions of use and it will be understood that, except as pointed out in the accompanying claims, the invention is not restricted to the particular construction shown and described herein.

I claim as my invention:

1. In a rotary kiln for the burning of cement raw material, the combination of a calcining section, a preliminary heating section from which the heated raw material is delivered to the calcining section, said preliminary heating section comprising a perforated shell closed at its upper end and a housing about the shell, means to deliver the raw material to the interior of the shell, means to deliver combustion gases from the calcining section to the interior of the shell, and means to compel the combustion gases to pass from the interior of the shell outward through the bed of material in the shell.

2. In a rotary kiln for the burning of cement raw material, the combination of a calcining section, a preliminary heating section from which the heated raw material is delivered to the calcining section, said preliminary heating section comprising a perforated shell closed at its upper end and a housing about the shell, means to deliver the raw material to the interior of the shell, means to deliver combustion gases from the calcining section to the interior of the shell, gas guards supported by the housing and in contact with the shell, and an exhauster connected to the housing.

POVL T. LINDHARD.
